UNITED STATES PATENT OFFICE.

FREDERICK K. SMITH, OF NEW YORK, N. Y.

DESIGN FOR A BOTTLE.

60,472.

Specification for Design. Patented Feb. 21, 1922.

Application filed January 2, 1920. Serial No. 349,067. Term of patent 3½ years.

To all whom it may concern:

Be it known that I, FREDERICK K. SMITH, a citizen of the United States, residing at the city of New York, in the county of New York and State of New York, have invented a new, original, and ornamental Design for a Bottle, of which the following is a specification, reference being had to the accompanying drawing, forming part thereof.

Figure 1 is a side view.

Fig. 2 is a top plan view, and
Fig. 3 an end view.

What I claim is:

The ornamental design for a bottle as shown.

FREDERICK K. SMITH.
